UNITED STATES PATENT OFFICE.

JAMES H. STODDARD, OF LOS GATOS, CALIFORNIA.

BOWLING-ALLEY.

No. 919,086.

Specification of Letters Patent.

Patented April 20, 1909.

Application filed July 9, 1908. Serial No. 442,706.

To all whom it may concern:

Be it known that I, JAMES H. STODDARD, a citizen of the United States, residing at Los Gatos, in the county of Santa Clara and 5 State of California, have invented certain new and useful Improvements in Bowling-Alleys, of which the following is a specification.

My invention relates to an improvement in 10 bowling alleys and more particularly to that class known as box ball, and the object is to provide means whereby the pins when struck will sound an alarm or indicate the number of the pin struck.

15 The invention consists of certain novel features of construction and combinations of parts which will be hereinafter described and pointed out in the claims.

In the accompanying drawings Figure 1 is 20 a view of the ordinary alley; Fig. 2 is a top plan view of the pins and connections; Fig. 3 is a longitudinal vertical sectional view of a portion of the device, and Fig. 4 is an end view of the pins.

25 A represents the usual alley, and 1, 1 are pins suspended on a rod 3, which is supported in the sides of the alley. These pins are supported above the floor of the alley a certain distance and the pins are separated

30 sufficiently from each other to permit of the ball passing between the pins or between the pins and the sides of the alley. The pins are preferably weighted at their lower ends to insure their returning to their normal position after being struck. A bar 4 extends 35 transversely of the alley and is connected to the sides thereof and affords a stop to limit the forward movement of the pins on their return to their normal position after being

40 struck. A rail 5 is supported between the sides of the alley at the rear of the pins, and extending longitudinally of the rail are wires 6 and 7, the wire 6 being connected to a battery 8, and the wire 7 connected up with the

45 annunciator 9, and leading from the annunciator to the battery is a wire 10. Extending across the wires and in contact therewith are contact arms 11, 11. These arms are secured to the rail 5 and rest upon the tops 50 of the pins 1, 1. Along the upper edge of the pins and on the rear side thereof are contact

plates 12, 12, which are adapted to cause the connection with the contact arms when the pin is struck and caused to swing rearwardly. Through this connection the annunciator is 55 sounded.

From the foregoing it will be seen that as the pins are struck contact will be made between the contact arms and pins whereby an alarm is given indicating that a pin has 60 been struck.

It is evident that more or less slight changes might be resorted to in the form and arrangement of the several parts described without departing from the spirit and scope 65 of my invention, and hence I do not wish to be limited to the exact construction herein set forth, but:—

Having fully described my invention, what I claim as new and desire to secure by Letters 70 Patent is:

1. In a bowling alley, the combination with pins suspended therein, of a rail, contact arms supported on the rail and in engagement with the pins, an annunciator, 75 means connecting the contact arms with the annunciator, and contact plates on the pins adapted to engage the contact arms when the pin is struck creating a circuit for operating the annunciator.

2. In a bowling alley, the combination with pins suspended therein, of a rail secured in the rear of the pins, contact arms supported upon the rail and in engagement with the pins, a second rail mounted in front of 85 the pins for limiting their forward movement, an annunciator, means connecting the contact arms with the annunciator, and contact plates on the pins adapted to engage the contact arms when the pin is struck creating 90 a circuit for operating the annunciator.

3. In a bowling alley, the combination with pins suspended therein, of a rail, contact arms supported upon the rail and in engagement with the pins, an annunciator, means 95 connecting the contact arms with the annunciator, and contact plates secured in recesses on the pins adapted to engage the contact arms when the pin is struck creating a circuit for operating the annunciator.

4. In a bowling alley, the combination with pins suspended therein, of a rail, con-

tact arms supported upon the rail and in engagement with the upper surfaces of the pins, beveled recesses formed in the pins, contact plates secured in the recesses below the upper surface of the pins, an annunciator, and means connecting the contact arms and the annunciator whereby the annunciator is operated when the pins are struck and a cir-

cuit made by the contact plates coming into contact with the contact arms.

In testimony whereof I affix my signature, in the presence of two witnesses.

JAMES H. STODDARD.

Witnesses:

ANDREW C. ROBERTSON,
W. A. STIDSTON.

It is hereby certified that in Letters Patent No. 919,086, granted April 20, 1909, upon the application of James H. Stoddard, of Los Gatos, California, for an improvement in "Bowling-Alleys," errors appear requiring correction, as follows: In the drawings forming part of said patent the reference-numeral 5 should appear to indicate the rail; 6 and 7 should indicate wires extending longitudinally of the rail; 8 the battery; 9 the annunciator, and 10 the wire leading from the battery to the annunciator; and that the said Letters Patent should be read with these corrections therein that the same may conform to the record of the case in the Patent Office.

Signed and sealed this 8th day of June, A. D., 1909.

[SEAL.]

C. C. BILLINGS,
Acting Commissioner of Patents.
